UNITED STATES PATENT OFFICE.

ERNEST UNGER, OF NEW YORK, N. Y.

HAIR-WAVING DEVICE.

Application filed January 18, 1924. Serial No. 686,968.

To all whom it may concern:

Be it known that I, ERNEST UNGER, a citizen of the United States, and resident of New York city, in the county of New York and State of New York, have invented certain new and useful Improvements in Hair-Waving Devices, of which the following is a specification.

The invention relates in general to a device for enclosing hair in treating the same, and specifically relates to an improved form of composition pad commonly known as a steam pad used in treating and protecting the hair while practicing the art of permanent hair waving.

In the art of permanently waving hair on a person's head it is a usual practice to wrap a strand of hair A on a waving rod B, to protect the hair under treatment with certain protecting substances, usually a mixture of saline powders, hereinafter referred to as a hair treating substance or material, and then to subject the hair to an intense heating while enclosed by an electric heater. At present the hair heating materials are conveniently contained in an envelope to form a prepared pad which is wetted, wrapped about the coiled portion of the hair, and held in place by a tube, usually formed of paste-board, and over which paste-board tube is slipped an electric heater. In order to close the wrappings thus formed at the end adjacent the head, it is a usual practice to crimp the paste-board tube and to close the same on to the uncoiled end of the strand by means of a tied string, or by the use of some form of closing clip. This closing of the end which is necessary to retain the steam and vapor in contact with the hair is not always satisfactory, leakage occurs and besides it is difficult and cumbersome to crimp the heavy paper tube.

The primary object of the present invention is to simplify and to render more positive than heretofore, the closing of the coiled portion of the hair strand within the steam pad while providing for the maximum protection of the contained hair.

Broadly, I attain this phase of the invention by providing a form of steam pad designed so that when wrapped on the coiled portion of the hair strand, the ends may be crimped into secure engagement with the unwrapped portion of the strand adjacent the head, and thus avoids any necessity of

crimping or otherwise closing the heavy paste-board or metal tube usually employed.

The utilization of the steam pad itself as the means for closing an end of the portion of the hair coil under treatment is conveniently attained by providing a border edge to the pad which edge will be free of the hair treating substance which is usually in the form of a flat cake. Reducing the thickness of an edge of the pad provides an end to the pad when wrapped into its usual cylindrical form and which end will be extremely flexible and easily crushed or crimped onto the uncoiled portion of the hair strand adjacent the head.

As an incident to the process of permanent hair waving, it is usual to subject the hair to a hot vapor treatment identified as a "steaming" operation. Extremely high temperatures, well above the boiling point of water, are utilized in this treatment and extreme care must be utilized to prevent any accidental overheating of the hair. One means for attaining this is to insure the maintenance of a moist condition confined to the portion of the steam pad which contacts with the coiled strand and numerous attempts have been made to conserve the available moisture.

Accordingly, another object of the invention is to provide an improved form of steam pad which will possess all of the advantages of the present conventional form of pad and which additionally will provide means for receiving, storing and gradually dispensing moisture to the enclosed hair coil when the same becomes dry incidental to the heating step of the hair waving operation.

Broadly this phase of the invention is attained by incorporating in the flexible steam pad of a porous material which has high capacity for moisture absorption. One substance which peculiarly meets the requirements of this situation is flannel. The present disclosure accordingly features a steam pad which is formed initially of a plurality of superposed layers of flexible material and one of which layers includes a strip of flannel for the purpose of absorbing water and thus constituting, when wetted and heated, a source of steam supply positioned immediately adjacent the coiled hair which it is designed to protect.

Various other objects and advantages of the invention will be in part obvious from

an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

10 Figure 1 is a view in axial section of a hair containing unit in position for coiling a strand of hair and including a steam pad constituting a preferred embodiment of the invention and wrapped into cylindrical form about the hair.

Figure 2 is a perspective view of a pad in its original flat, unwrapped condition, and with parts broken away to show the several layers composing the same;

20 Figure 3 is a transverse sectional view taken on the line 3—3 of Figure 1 looking in the direction indicated by the arrows,

Figure 4 is a perspective view of the tube closing and pad crimping cap.

25 In the drawings and referring particularly to the showing of the complete hair protecting unit in Figure 1 it is noted that the strand of hair A includes a coiled portion C and that the portion D between the coiled 30 portion and the head is uncoiled, straight and is formed usually of the thickness of a thin lead pencil. The pad 10 which is marketed in the flat rectangular shape shown in Figure 2 is rolled so as to extend 35 about both the coiled and uncoiled portion of the strand. One novel feature of this disclosure is that the protecting steam pad encircles both the coiled and uncoiled parts 40 of the strand and extends beyond the adjacent end of the rod which is contained entirely within the tube E. Over the steam pad is telescoped a tube E, which is usually of paste-board and the end adjacent the head is closed by a closing cap or clip F.

45 It is understood that the heater which is usually of a spool shaped form is slipped over the tube E and slides down towards the head as close as is convenient or desirable.

Referring to the prepared pad 10 it is 50 noted that it follows somewhat conventional structure in that it includes a flat envelope of textile material, such as muslin, comprising an outer layer 11 and an inner layer 12, overlapping to form a turned edge 13 55 and having the other three edges secured by lines of stitching 14. The envelope contains a hair treating substance usually a saline powder and preferably in the form of a flat cake. Centrally positioned within 60 the cake is a layer of flannel 15 which thus forms an outer layer 16 of powder and a similar inner layer 17 separated by the flannel. It is within the scope of this disclosure to soak the flannel in a solution of the hair 65 protecting material so that the flannel may

become impregnated with the material. However, it is preferable to have the flannel free of filling material so that it may absorb water to its maximum capacity. The inner side of the pad is designed to contact with the hair and has its muslin side 12 backed by a layer of absorbent paper 18 and the outside of the pad, that is the side which is designed to be engaged by the tube E and clip F, is formed of some suitable form 70 of non-leak paper 19. The paper 19 is preferably of such character as will provide a slippery surface.

It is a feature of this disclosure that the cake of hair treating substance is confined 80 to the center of the pad so as to leave a marginal portion 20 which does not contain any of the bulky powder. This leaves the edge which is designed to enclose the uncoiled portion D of the hair extremely 85 flexible and easily crimped about the hair. This construction permits the tying of the projecting portion of the pad onto the uncoiled part of the strand or the engagement 90 of this part by means of a clip as illustrated 95 in Figure 1.

While it is required simply that the edge which extends through the clip F be reduced in thickness and made flexible the device disclosed has its opposite edge 21 similarly 100 reduced in thickness so that the pad may be cut in half if desired and both ends used to enclose uncoiled portions D adjacent the head.

In operation the hair is coiled on the rod; the pad is wetted, if desired, and disposed so as to position the powder cake about the coiled part C and to permit the edge portion, which is free of the powder, to extend about the strand portion D and as close as desired to the head of the person under treatment. The reduced end of the pad is then crimped about the strand D and secured in its tube closing position by tying 110 the end with a string as suggested at 22 or by means of a clip as shown at the right of Figure 1. When so closed it will be understood that the bore of the pad containing the hair forms, in effect, a closed steam 115 space. The tube E is then telesconed onto the pad and closing clip. It is understood that the non-leak paper covering to the pad provides a slippery surface which facilitates the easy insertion and removing of 120 the tube E.

It is a feature of this disclosure that the tube E can be brought up closer to the head than is possible with similar devices now known, and in this way the resulting wave 125 in the treated hair can be brought up close to the head. A suitable electric heater, (not shown) is positioned on the tube E and the assemblage is ready for the heat treatment.

During this heat treatment steam will 130 form in the steam chamber about the coiled

strand and little if any of this steam escapes. It has been found that using the flannel insert maintains a constant supply of moisture so that by the use of the pad herein disclosed it is possible to maintain a limited but constant supply of moisture to compensate for any of the steam which may escape from the device.

Due to the tight closing of the ends of the pad about the hair strand, a close packing is provided and possibility of steam escaping onto the head is practically eliminated. Using the pad disclosed results in a saving of time in the operation due among other reasons to the fact that the non-leak paper defining the outer surface of the pad permits the tube E to be quickly removed and the usual "freezing" has been eliminated.

Having thus described my invention, I claim:

1. A unit for use in waving hair comprising a pad for enclosing a coiled strand of hair, said pad having an end portion for encircling a straight part of the hair strand adjacent the coil, a closing clip for crimping the portion into engagement with said part and a tube enclosing the coil and acting to secure the clip in place closing the tube.

2. A unit for use in waving hair comprising a waving rod adapted to have a coil of hair wrapped on the same, a steam pad for enclosing one end of the rod and the hair thereon, and projecting beyond said end of the rod, a closing clip for engaging said projecting end of the pad and a tube enclosing the part of the hair coil wrapped on the rod and in telescopic engagement with the clip to hold the same in place.

3. A unit for use in waving hair comprising a rod adapted to have a strand of hair with a part coiled on the rod and a straight part extending from the coiled part, a pad inclosing both the coiled and the straight parts of the hair strand, a tube telescoping the part of the pad enclosing the coiled hair and a clip for closing an end of the pad about the straight part of the hair strand and for closing one end of said tube.

4. A unit for use in waving hair comprising a pad adapted to be wrapped about a coiled part of a strand of hair and having a part adapted to be wrapped about the uncoiled end of the strand, a tube for enclosing the coiled part and a clip for engaging the part of the pad wrapped about the uncoiled part and closing both the engaged end of the pad and the tube and in frictional engagement with the tube.

5. A unit for use in waving hair comprising a pad adapted to be wrapped about a coiled part of a strand of hair and having a part adapted to be wrapped about the un-

coiled end of the strand, the outer surface of said pad being formed of a flexible material having a slippery surface, a tube for enclosing the coiled part of the strand and easily slidable over said slippery surface, and a closure having a telescopic fit in the tube and engaging the flexible material of the pad enclosing the uncoiled end of the strand to close one end of the pad.

6. A steam pad for use in waving hair comprising an envelope formed of textile material, a hair treating substance within the envelope and a layer of flannel within the substance spaced from opposite faces thereof and adapted to secure and retain moisture when in use and to feed the same to the substance.

7. A flat steam pad for use in waving hair comprising an envelope formed of textile material, a layer of absorbent paper within the envelope, a layer of flannel and a layer of hair treating substance between said paper layer and one side of the envelope.

8. A flat steam pad for use in waving hair comprising an envelope formed of textile material, a layer of absorbent paper within the envelope, a layer of flannel, a layer of hair treating substance between said paper layer and one side of the envelope and a layer of non-leak paper on the outer face of said side of the envelope.

9. A flat steam pad including an envelope formed of textile material, a body of hair treating substance within the envelope and moisture absorbing means within said body surrounded thereby and adapted, when the pad is subjected to a steam treatment, to condense the steam, absorb some of the resulting moisture and feed the same to said substance.

10. A steam pad for use in waving hair comprising an envelope, a hair treating substance contained therein, and moisture absorbing means within the substance for receiving and storing moisture and for gradually feeding the moisture to the substance as it becomes dry during the use of the pad.

11. A steam pad including an inner layer of flannel having a hair treating substance on opposite sides thereof, a layer of absorbent paper on one side of inner layer and a layer of non-leak paper on the opposite side.

12. A steam pad which when flat is formed of a series of superposed layers comprising a layer of muslin, a sheet of absorbent paper, a hair treating substance, a layer of flannel, a hair treating substance, a layer of muslin and a sheet of non-leak paper.

Signed at New York city in the county of New York and State of New York this 7th day of January, A. D. 1924.

ERNEST UNGER.
